INVENTOR

Edward Carnduff,

BY

Albert C. Pennington,
ATTORNEY

UNITED STATES PATENT OFFICE.

EDWARD CARNDUFF, OF COLFAX, IOWA.

FASTENING DEVICE.

SPECIFICATION forming part of Letters Patent No. 746,670, dated December 15, 1908.

Application filed June 3, 1903. Serial No. 159,895. (No model.)

To all whom it may concern:

Be it known that I, EDWARD CARNDUFF, a citizen of the United States of America, and a resident of Colfax, in the county of Jasper and State of Iowa, have invented certain new and useful Improvements in Fastening Devices, of which the following is a specification.

My invention relates to improvements in a fastening device particularly adapted for removably securing tools or implements upon their respective handles, and I shall describe the same as applied to miners' picks, which demand the frequent replacement of dulled or broken pick-blades upon the handles.

In my improved device I have endeavored to provide a construction that will most easily and securely mount the pick-blade or other tool upon its handle, while avoiding the unnecessary wear of the threaded parts securing it in place, and prevent as well the loosening of said tool while in use, although permitting the most ready removal and replacement of the pick-blade.

The common mode of mounting pick-blades upon their handles is by means of screw-bolts, which are inserted in tapped holes in metallic sockets attached at the ends of said handles and adapted to receive said blades, as exemplified in Patent No. 356,412, dated January 18, 1887. The frequent tightening and loosening of these bolts, however, which must be completely withdrawn and reinserted each time the pick-blade is changed, wears the threads, thereby preventing the blade from being securely fastened in place, and also requires more time to accomplish than is necessary. My improvements overcome these deficiencies observed in the devices of the prior art, as well as others, as will appear from the following specification.

The accompanying drawings will enable me to explain definitely my said improvements, wherein—

Figure 1 is a side view of a miner's pick constructed in accordance with my invention, the parts being broken away and cross-sectioned to make the details quite clear. Fig. 2 is a top view of the pick-blade with the fastening-bolt and washer removed. Fig. 3 illustrates in its closed position the hinged

washer preferably employed therein, and Fig. 4 shows the same opened to release the bolt and pick-blade. Fig. 5 is a detail of the fastening-bolt; and Fig. 6 is an end view of the hinged washer, showing the depending pins. 55

The same characters of reference are employed to designate similar parts in each of the several figures of the drawings.

At the outer extremity of handle *h* is permanently mounted the metallic socket or cap *c*, suitably shaped to receive the removable pick-blade *p* or other tool and having retaining-ribs *c*², which enter corresponding depressions upon the under side of said blade. 60

A central tapped hole *c*³ within the socket *c* is adapted to seat the fastening-bolt *b*, the hexagonal head of the latter being of sufficiently small size to pass through the vertical aperture *p*² in said pick-blade and permit the removal from or the adjustment of said blade *p* upon the socket. Said bolt is provided with a lower left-hand threaded portion *b*², entering the tapped socket, and a slightly larger right-hand threaded portion *b*³, adapted to receive the ribbed or trishoulder nut *n*, fitting snugly within the opening *p*². Said opening, as seen in Fig. 2, is cut to conform to the nut and prevents the latter from turning with the bolt, while beneath the nut are disposed two springs *s* *s*² of different tensions or 75 strengths.

Beneath the head of the bolt *b* is disposed the hinged washer *w*. (Shown in plan view in Figs. 3 and 4.) This comprises two separable hinged parts, the opening in which when 85 the device is closed being only substantially the size of the upper portion of the bolt, and in consequence the bolt-head engages the upper surface of the washer, as shown in Fig. 1, thereby retaining the pick-blade in position under normal conditions. At such times in order securely to retain the washer in position a pin or lug *w*² is provided in each of the outer or separable end portions of the washer, which pins are adapted to enter a shallow recess *p*³ in the upper surface of the pick-blade. In this position a slight downward turn of the bolt within its tapped hole in the socket serves rigidly to fasten the pick-blade upon the handle and securely lock the 90 100

washer in its closed position beneath the bolt-head. This is readily accomplished by means of a small wrench applied to the bolt-head.

The downward movement of the bolt is magnified with respect to the nut n , which is also forced downward upon the bolt by the larger thread cut thereon against the tension of the heavy and lightsprings s s^2 , thereby compressing them beneath said nut. Similarly the pick-blade may be loosened and removed from the socket and handle by a partial reverse turn of the bolt, thus loosening the retaining part or washer w sufficiently to free the lugs or pins w^2 from the recess p^3 , whereupon said washer may at once be removed from beneath the bolt-head and the pick-blade may be slipped from the bolt and socket.

It will be seen that the threaded portions of the bolt and socket are subjected to a minimum of wear and are at all times in engagement throughout almost their entire length, while the removal and secure replacement of a pick-blade are very readily and easily effected.

25 The nut n centrally stays the pick-blade, the opening in which it snugly fits, and under the influence of the spring-pressure it assists in retaining the bolt in its retracted position and in preventing the loosening of said bolt. 30 Moreover, the entire device is practically integral. Hence the accidental loosening, separation, and loss of the removable parts (the retaining part or washer and the pick-blade) are rendered most unlikely.

35 Having now described and shown an appliance fully embodying my invention, I claim as new, and desire to secure by Letters Patent, the following:

1. The combination with a suitable socket or receptacle, of a rotatable part mounted therein, a hinged retaining part or washer,

and a tool or device adapted to be secured by the rotatable part to said socket beneath the hinged washer, substantially as set forth.

2. The combination with the socket s , of 45 the bolt b mounted therein, the separable retaining part or washer w , and the tool p adapted to be removably secured to the socket beneath said separable retaining part, substantially as set forth. 50

3. The combination with a handle and its terminal socket, of a tool-fastening device comprising a threaded bolt mounted in said socket and a separable retaining part or washer, and a removable tool suitably cut 55 away to receive said bolt and washer, adapted to be secured to the socket beneath the washer and bolt-head, substantially as set forth.

4. The combination with a handle and its terminal socket, of a bolt mounted in the latter, a separable retaining-washer, and a removable tool or part suitably cut away to receive the bolt and washer and engage the latter to prevent its accidental opening, substantially as set forth. 60

5. The combination with a handle and its terminal cap or socket, of a tool-fastening device comprising a threaded bolt mounted in said socket, a spring and the tension-nut thereon, a removable tool or device suitably 70 cut away to accommodate said parts, and a separable retaining part or hinged washer adapted to engage the bolt-head and tool and secure the latter to the socket, substantially as set forth. 75

Signed at Colfax this 9th day of May, 1903, in the presence of two subscribing witnesses.

EDWARD CARNDUFF.
